ALARM FOR ALUM FEEDER

Will C. Lingerfelt, Morristown, Tenn., assignor to American Enka Corporation, Enka, N. C., a corporation of Delaware

Application October 20, 1952, Serial No. 315,691

4 Claims. (Cl. 340—239)

This invention relates to the addition of controlled amounts of solid material to a liquid and, more particularly, to an alarm device for detecting and announcing stoppage in the flow of a particulate solid material being fed to a liquid.

In the art of water purification, it is frequently necessary to add alum in measured quantities in order to precipitate out mud and other solid contaminants. One way in which this may be accomplished is to feed continuously small quantities of alum from a shaker container into a mixer vessel containing the water to be treated. In the event there is a stoppage in the flow of alum from the shaker container to the water, the dosage is incorrect and serious consequences may result.

There are, of course, a great many devices known to the art for detecting stoppage in the flow of a solid material. Most of these devices, however, are located in the feed line and there is always the possibility that stoppage will occur between the location of the indicating device and the discharge outlet. It is, therefore, an object of this invention to provide a highly reliable means for detecting stoppage in the flow of a solid being added to a liquid for admixture therewith regardless of where the stoppage actually occurs.

According to the present invention it is proposed to provide a target within the mixing area and to supply the material to be added to that target in such a way that interruption in the supply of the solid to the target will result in an alarm.

Other objects and advantages of the present invention will be apparent upon consideration of the following detailed description thereof in conjunction with the annexed drawings wherein:

Figure 1 is a view partially in vertical section and partially in side elevation of an alum mixing tank equipped with an alarm device according to the present invention.

Figure 2 is a fragmentary top plan view of the apparatus of Figure 1; and

Figure 3 is a view partially in elevation and partially in vertical section of the top of the tank of Figure 1 taken from a position 90° away from the viewing position of Figure 1.

In the drawings the numeral 10 designates a mixing tank of glass or porcelain. The water to be treated is introduced into and withdrawn from this tank by instrumentalities not shown. The alum to be mixed with the water in the tank 10 is fed from a shaker, not shown, through a chute 11 located at the top of the tank. The chute 11 is roughly half round in cross section as can be seen upon reference to Figure 2. The alum fed through the chute 11 falls through an unconfined path to the water level in the tank. In the unconfined path of fall, there is located a target 12 in the form of a bell or inverted funnel having thereon circumferential ridges at 13 and 14. It can be seen, therefore, that the alum, falling vertically from the chute 11, will strike the target and, because of the ridges 13 and 14, will be held thereby to

2

a considerable extent. Thus, during operation, the weight of the target 12 is increased by the weight of the alum thereon. With this in mind, the target is supported in position by a lever 15 which is in the form of a bent rod of glass or metal anchored to the target at one end and at the other end pivotally mounted at 16 to a switch assembly frame 17. A spring 18 acting in tension is attached to the rod 15 close to the pivot 16 but between that pivot and the target 12, and that spring acts to hold the target 12, when it has its normal weight, in the desired position vertically below the bottom of the chute 11. On the other hand, the bias of the spring 18 is such that the target 11 when free of alum and hence below normal weight, is moved in an anti-clockwise arc a small distance away from the position shown in Figure 1.

It will be noted from Figure 1 that the rod 15 has a substantially vertical portion depending from the pivot at 16 and a sloping portion extending to the target. A tube 19 is positioned within the cover of the tank 10 and that tube lies in alignment with the sloping portion of the rod 15. The tube 19 is so located that its lower end is immediately adjacent the bend in the rod 15 so that water issuing from the tube 19 will flow along the sloping portion of the rod 15 and bathe the target 12. The wet surface of the target 12 causes a certain amount of alum to adhere to the target and thus increase its weight. By this arrangement water is supplied through the tube 19 at a rate which washes the alum off the target 12 about as fast as the alum is supplied to the target through the chute 11. The normal amount of water on the target, the normal amount of alum on the target and the weight of the target itself counter-balance the pull of the spring 18 and hold the target in the Figure 1 position except when there is a deviation from normal weight. If, however, there is an interruption in the flow of alum in the chute 11 or anywhere in the feed system thereabove, the existing alum is quickly washed off the target by the water continuously supplied through the tube 19, then the normal total weight of the target will be decreased enough so that the spring will be able to move the target slightly in an anti-clockwise direction. To take advantage of this movement there is an electric contact switch 20 in the box 19. This switch is spring biased to circuit closing position and is held in circuit open position by the end of rod 15 above the pivot at 16 when the target is in the Figure 1 position. On the other hand, when the alum is washed off of the target 12 and the target is moved by the action of the spring 18, the upper end of rod 15 moves counterclockwise and releases the switch 20 which then closes a circuit which may include any sort of an audible or visual alarm diagrammatically indicated at 21.

The details of the switch 20 are only shown schematically since the switch itself and the alarm in circuit therewith form, per se, no part of the present invention. Nevertheless, a schematic alarm is designated at 21. The cord 22 is the power cord for supplying current to the alarm 21, through the switch 20.

It is apparent that various modifications of the present invention lie within the scope thereof and that the type of alarm and its position may be varied depending upon operating conditions.

What is claimed is:

1. An alarm device for announcing variation from normal in the flow of a solid material that comprises means to discharge solid material, a target, means balancing said target in the discharge path of said material, means to supply a fluid to remove solid material from said target at a rate commensurate with the normal rate of delivery of solid material thereto so that the target has a substantially constant weight of material thereon dur-

3
ing normal operation, and means responsive to unbalance of said target to actuate an alarm.

2. An alarm device for announcing failure in the feed of solid material that comprises means to discharge solid material, a target in the discharge path of said material, means to supply a fluid to remove solid material from said target at a rate commensurate with the rate of delivery of solid material thereto so that the target has a substantially constant weight of material thereon during normal operation, and means responsive to reduction in weight of material on target below said substantially constant value to actuate an alarm.

3. An alarm device for announcing failure in the feed of a solid material that comprises a container, a solid material feed chute for continuously discharging solid material into said container, a target, means movably balancing said target in the path of the material discharged into said container, means to wash material continuously from said target into said container, the target having a substantially constant weight of material thereon during normal operation, and means actuated in response

4
to unbalance of said target in response to marked reduction in weight of material thereon to actuate an alarm.

5. An alarm device for announcing failure in the feed of alum to a liquid purification system that comprises, a liquid container, an alum delivery chute for continuously discharging into the top of said container, a conical target, means resiliently balancing the target in the container vertically below the delivery chute and in the path of the alum, means to bathe the target continuously to wash the alum therefrom into the tank, the target having a substantially constant weight of alum thereon during normal operation, and means actuated by said suspending means in response to unbalance of said target incident to reduction in weight of alum on said target to actuate an alarm.
